ABSTRACT: An adhesive applying device for a shoe lasting machine with heated nozzles, each nozzle having outlets and an inlet through which a solid rod of thermoplastic adhesive is fed for melting in the nozzle and extrusion through the outlets onto the generally flat forepart of a shoe insole bottom.

Inventor
Gerard J. Marquis
By his Attorney
Vincent A. White

ADHESIVE APPLYING DEVICES

BACKGROUND OF THE INVENTION

1. Field of the Invention

The invention relates generally to improvements in adhesive applying devices for shoe lasting machines. In particular, the improvement is directed to nozzles adapted to apply molten thermoplastic adhesive along the margin of the generally flat forepart of an insole bottom for securing the forepart margin of a lasted shoe upper to the bottom of the insole.

2. Description of the Prior Art

Thermoplastic adhesives are commonly used to secure portions of the margins of lasted shoe uppers to the bottom of insoles. To obtain optimum benefits from such adhesives it has been found most advantageous to apply the adhesive in a molten condition during the lasting operation. Devices for applying thermoplastic cement in lasting machines have been developed of the type shown in U.S. Pat. No. 3,422,797 granted in the name of Karl V. Becker. Such a device provides for a nonadjustable nozzle which is suitable for applying cement about the toe end of the insole bottom extending heelwardly only about to the tip line of the shoe where the contours of shoes of various styles and sizes do not vary to any great degree. The tip line is commonly understood in the shoemaking art to extend widthwise approximately at the midpoint of the generally flat forepart of the bottom of the shoe. The opposite sides of the shoe at the tip line are substantially equidistant from the centerline of the forepart and have the same general shape for right and left shoes. However, the marginal contour of the remainder of the generally flat forepart of the insole extending heelwardly from the tip line to about the ball line of shoes where the shoe bottom curves heightwise toward the heel end; varies considerably between sizes, styles and especially rights and lefts.

It would be possible to provide a nozzle such as shown in the Becker patent which extended heelwardly to the ball line, but it would be impractical due to the necessity of changing such a nozzle whenever a different size and/or style shoe was to be operated upon. Furthermore, since right and left shoes vary drastically in contour, separate machines would need to be provided for right and left shoes or such shoes would need to be processed separately. This would not be economical either in investment for machinery or in manpower.

As a partial solution to this problem particularly related to the forepart of shoes, thermoplastic cement has been preapplied to the insole in this area and allowed to harden as a separate operation before the lasting operation. The cement was activated by the application of heat by units such as disclosed in U.S. Pat. No. 3,302,225. Such heat units were adapted to be adjusted to the contour of various sizes, styles and right and left shoes. Such a solution, however, required a separate adhesive applying and drying step and could not take full advantage of the qualities and economics of thermoplastic adhesives.

SUMMARY OF THE INVENTION

Accordingly, it is an object of the invention to provide a device which is capable of applying molten adhesive to an insole bottom along the entire margin of the generally flat forepart of the insole. To this end the machine is provided with a nozzle similar to that disclosed in the Becker patent for applying adhesive around the toe end of the insole to about the tip line and is also provided with a pair of adjustable nozzles which apply adhesive heelwardly along opposite sides of the insole to the ball line. The pair of nozzles are curved to suit the average side contour of a wide variety of shoe styles and also are adjustable widthwise to suit both right and left shoes alternately.

The above and other objects and features together with novel details of construction will now be described with particular reference to the embodiment shown in the drawings and thereafter pointed out in the claims.

BRIEF DESCRIPTION OF THE DRAWINGS

FIG. 1 is a side elevation of a shoe supporting and adhesive applying means for a lasting machine embodying the present invention;

FIG. 2 is a plan view of a portion of the mechanism shown in FIG. 1;

FIG. 3 is a plan view of a portion of the mechanism shown in FIG. 2 with adhesive applying nozzles in a neutral position;

FIG. 4 is a view similar to FIG. 3, but with the mechanism adjusted for operating on a left shoe;

FIG. 5 is a section on line V-V of FIG. 4; and

FIG. 6 is a section on line VI-VI of FIG. 4.

A typical machine with which the adhesive applying mechanism of the present invention may be employed is described in U.S. Pat. No. 3,164,852 granted Jan. 12, 1965 in the name of R. M. Bowler et al. The machine includes a shoe rest 2 (FIGS. 1 and 2 and referred to by the same reference character in said patent) which supports a last on which an upper and an insole are loosely assembled to position the last heightwise as well as to support it against the action on the upper of a toe gripper and a plurality of side grippers (not shown). The machine is also provided with wipers 4 which act after the grippers have tensioned the upper to wipe the upper downwardly over the sides of the last and inwardly over the bottom of the insole on the last. The margin of the lasted upper is secured to the bottom of the insole by a band of thermoplastic adhesive which is applied to the generally flat forepart of the insole before the wipers move the upper inwardly over the bottom of the insole on the last. As disclosed herein, the mechanism for applying the thermoplastic adhesive comprises a generally V-shaped toe nozzle member 6 which engages the bottom of the insole around the toe end to about the tip line of the shoe and a pair of adjustable side nozzles 8 which engage the insole bottom along opposite sides heelwardly to about the ball line of the shoe.

The toe nozzle is generally similar to that disclosed in said Becker patent and comprises a V-shaped nozzle member 10 which is removably secured to the upper side of a holder 12. The holder is supported on a flange 14 of a sleeve 16 for universal self-leveling action by means of a post 18 secured to the flange and springs 20 which surround guide rods 22 and are disposed between the lower ends of bosses 24 on the holder and the flange 14. At their upper ends the guide rods 22 are loosely secured to the holder so that the nozzle can tip or rock slightly about the post 18 and thus level itself on the insole bottom on the shoe rest 2. The sleeve 16 is slidably mounted on a post 26 which carries the shoe rest 2. At the appropriate time in the machine cycle before the inward wiping movements of the wipers 4 the toe nozzle is moved heightwise into self-leveling engagement with the insole bottom by a fluid pressure cylinder 28 which acts through a link 30 connected to the sleeve.

The side nozzles 8 each comprise a nozzle portion 32 which has a curvature (FIGS. 2-4) which generally corresponds to the average curvature of the sides of shoes from about the tip line to about the ball line. As seen in FIG. 5, the nozzle portion 32 is secured to a body 34 by a T-slot connection. At its

toeward end the body is mounted on the upper end of a post 36 which is mounted for rotation in a bracket 38. The post is connected to the body 34 by a pin and slot connection 40 which, as seen in FIG. 5, permits downward motion from the position shown against the action of a spring 42 extending between the body and a flange 44 of the post. The flange 44 is supported on an arm 46 which rests on the upper surface of the bracket 38 as best seen in FIGS. 1 and 5. The post extends downwardly through an ear on the bracket and has a compressed spring 48 extending between a collar 50 and the under side of the ear to yieldingly maintain the post in the position shown. The heelward end of the body 34 is supported on the upper end of a post 51 (FIG. 1) by a pin and slot connection 52. The post 51 is provided with a spring 54 which urges the body 34 heightwise as limited by the connection 52. A flange 56 of the post rests on the heelward end of the arm 46

and the post passes through the arm and is connected to one end of a link 57, (See also FIGS. 2—4) the other end of the link being connected to one arm of an adjusting lever 58. The adjusting lever 58 is pivoted at 59 on a portion of the bracket 38 and, as seen by comparing FIGS. 2 and 4, is adapted to swing the side nozzles about the posts 36 widthwise in unison to adjust the nozzles to apply adhesive on right and left shoes alternately. The lever 58 is provided with a handle 60 which when swung to the left as seen in FIG. 2 adjusts the nozzles to operate on a right shoe. By swinging the handle to the right as seen in FIG. 4, the nozzles may be adjusted to operate on a left shoe.

For moving the side nozzles bodily heightwise into and out of engagement with the insole bottom the bracket 38 is secured to a plate 62 (FIG. 1). The plate is provided with depending rods 64 arranged to slide heightwise in suitable bearings 66 in a main bracket 68 fixed to a portion of the machine frame. The upper end of a piston rod 70 of a cylinder 72 is fixed to the plate 62. The lower end of the cylinder is fixed at 74 to the bracket 68. The cylinder is provided with ports 76, 78 for causing movement of the piston rod heightwise. By admitting fluid under pressure through the port 76 the nozzles 8 are moved up into engagement with the insole bottom and by admitted fluid under pressure into the port 78 while exhausting the port 76 the nozzles are moved down from the insole and out of interference with the inwiping movement of the margin of the lasted upper.

From the foregoing, it is apparent that the forepart nozzle 6 is moved heightwise into engagement with the insole bottom at the appropriate time in the machine cycle by the cylinder 28 while the side nozzles 8 are moved up at the same time into engagement with the insole bottom by the cylinder 72. The nozzles by their flexible mountings are self-leveling on the insole bottom to accommodate any slight curvature of the generally flat forepart of the insole. In addition, the side nozzles 8 may be adjusted differentially widthwise in unison as seen by a comparison of FIGS. 2 and 4, to accommodate right and left shoes. After the nozzles are moved up into engagement with the insole bottom, adhesive is extruded from the nozzles 6 and 8 to apply a band of adhesive along the margin of the generally flat forepart of the insole bottom to about the ball line where the insole bottom curves heightwise toward the heel end of the shoe. To this end, the side nozzles 32 (FIG. 5) are each provided with a channel 80 along which molten adhesive can flow from outlet openings 82. The outlets 82 lead from a closed channel 84 in nozzle 32 which in turn communicates with a melting passage 86 in the body 34. The lower end of passage 86 also forms an inlet which is connected by a fitting 90 to a flexible tube 91 of non-heat-conducting material. The fitting 91 is connected to one end of a coil 92 of heat conductive material which surrounds the tube 91 and is connected at the other end to a fitting 94. The fitting 94 is secured to the tube 91 and the coil 92 acts as a spring which is slightly stretched to urge the tube firmly into the fitting 90. In addition to holding the tube 91 in the fitting 90 the coil 92 also radiates any heat that may be conducted from the body 34 along fitting 90 to maintain the upper end of the tube 91 in relatively cool condition. Thermoplastic adhesive in solid rod form 95 is fed from a reel 97 (FIG. 1) through the tube 91 and inlet passage 86. The body 34 of each nozzle is provided with a heating element 88 and as the solid rod 95 is fed through the inlet passage 86 it is melted progressively and extruded in molten condition through the outlets 82. There is shown in FIG. 1 a suitable rod feeding device which is remote from the nozzles in any convenient location in the machine and which includes motors 100 and feed wheels 102 which engage and

feed adhesive rods 95 through the tubes 91 to both side nozzles 8. The adhesive feeding and extruding means for the toe nozzle 6 is identical to that provided for the side nozzles 8 and need not be further described herein.

5 The nozzle arrangement above described is adapted to apply molten adhesive to a wide variety of shoe styles as well as to right and left shoes alternately by adjustment of the handle 60. By reference to FIG. 1 it is apparent that a small size shoe such as that shown in full lines does not completely cover 10 the side nozzles 8, whereas a larger size shoe as shown in dash lines does. To prevent excessive adhesive being extruded from the side nozzles 8 and spilling over into the mechanism of the machine when a small size shoe is being operated upon, the heelward outlets of each side nozzle 8 is provided with individual valves as best seen in FIG. 6. Each valve is provided with a flange 96 adapted to close its associated outlet and is received in the channel portion 84 of the nozzle. Each valve is also provided with a grooved stem 98 which normally extends upwardly through an outlet and above the top of the nozzle 32. A 15 spring 100 underlies the flange 96 urging the valve into closed condition. As seen in FIG. 6, the heelmost valve is not engaged by the insole bottom, whereas the stems 98 adjacent thereto in a toeward direction are engaged and depressed to open the valves to permit extrusion of adhesive through the associated 20 outlets 82. Thus, it should be apparent that each of the nozzles 8 is adapted automatically to accommodate a variety of shoe sizes while minimizing excessive wastage of adhesive.

25 It should be obvious that the foregoing is intended to describe one preferred embodiment of the invention and that numerous substitutions of various elements embodied in the 30 illustrative device may be made without departing from the scope of the invention as set forth in the following claims.

I claim:

1. In a machine for lasting shoes in which the margin of the 35 forepart of a lasted shoe upper is adhesively secured to the forepart margin of an insole bottom, said machine having a generally V-shaped heated nozzle engageable with the toe end of the insole bottom for applying a band of adhesive along the margin around the toe end of the generally flat forepart of the 40 insole bottom, the improvement comprising

a pair of elongate heated nozzles engageable with the insole bottom along the margin at opposite sides of said generally flat forepart and extending from the heelward end of said V-shaped nozzle to the heelward end of said flat forepart where the insole curves heightwise toward the heel end of the shoe,

means for differentially adjusting each of said pair of nozzles widthwise of the shoe for general alignment with the marginal contours of the insoles of right and left shoes alternately,

each nozzle having outlets in the area engageable with the insole bottom and an inlet, and

means for feeding a solid rod of thermoplastic adhesive through the inlet of each nozzle whereby solid adhesive rods are progressively melted in said V-shaped nozzle and said pair of nozzles and extruded from the outlets to apply a substantially continuous band of molten adhesive along the margin of the generally flat forepart of the insole bottom.

2. A machine according to claim 1 in which the differential 60 adjusting means for each of the pair of nozzles includes means mounting said nozzles for swinging movements widthwise of the shoe about axes adjacent to the heelward end of said V-shaped nozzles for aligning the nozzles generally with the marginal contours of the insoles of right and left shoes alternately.
